GUIDE FOR CURRENT COLLECTORS.

1,405,270.

Specification of Letters Patent. Patented Jan. 31, 1922.

Application filed November 17, 1921. Serial No. 515,953.

To all whom it may concern:
Be it known that we, CYRUS B. BUCHANAN and CHARLES C. JOHNSON, citizens of the United States, residing at New York, in the county and State of New York, and Richmond, in the county of Henrico and State of Virginia, have invented certain new and useful Improvements in Guides for Current Collectors, of which the following is a specification.

Our invention relates to improvements in guides for overhead trolley current collectors.

One object of our invention is to provide a guide applied to over head double trolley wires so that at intersections, either by crossings, turnouts or switches, the current collector, used on motor vehicles running on the roadway or street beside the trolley, is deflected or thrown below the trolley wires and carried across the cross wires or switches and guided back upon the trolley wires.

Another object of our invention is to provide means for guiding the trolley head across the switch or crossing so that it will only have a limited lateral movement and prevent the head from engaging the wires and causing a short circuit through the trolley head and yet in no way interfering with the passage of the trolley wheels of the trolley cars passing therethrough, without their removal.

Another object of our invention is to provide a guard of this character whereby in the operation of a double overhead trolley system, in connection with a single overhead trolley system, both systems will operate without interference with each other.

A still further object of our invention is to provide a guard of this character which can be readily applied to the overhead wires without material change, thus permitting the use of regular standard equipment, it being unnecessary to provide expensive special equipment, for the purposes set forth. Our invention has certain details of structure and combinations of parts hereinafter more fully described.

In the accompanying drawings, Fig. 1 is a plan view of my guard applied to the trolley wires looking from above. Fig. 2 is a side elevation of Fig. 1. Referring to the drawings, 1 and 2 represent the two trolley wires, which, as will be

readily understood, may be supported in any desired manner. The wires as shown are provided with the switches 3 leading off to the tracks over which the car travels in leaving the main wires, all of which is well understood and needs no further description. Our improved guard comprises the two guard rails 4 and 5 which have their ends curved outwardly, as indicated at 6 and 7, and upwardly over the top of the trolley wires 1 and 2 and secured to blocks 8 fastened to the upper face of the wires, whereby the ordinary trolley wheel is free to pass on the lower face of the wire between the guard rails 5 and 22, 37 and 22, 34 and 31 and 43 and 34. The said guard rails 4 and 5 have connected thereto the hangers 9 and 10 which have their upper ends connected to the transverse bar 11 which extends outwardly above the wires and is connected to blocks 12 carried by the wires. The guard rail 5, as heretofore stated, is practically parallel with the wire 2, while the rail 4 has its inner end curved, as indicated at 13, parallel with the wire 14 of the branch line.

The inner end of the rail 4 is connected to the hanger 15 which has connected thereto the bar 16, which has its ends 17 and 18 extending a considerable distance beyond the trolley wires 14 and 2. A second bar 19 is arranged practically parallel with the bar 16 and the two bars are connected together at their outer ends beyond the trolley wires 2 and 14 by the guard rails 20, 21, 22 and 23, the same being supported by hangers 24 in the same manner as the guard rail 4 is connected to the bar 16. The guard rails 21 and 23 are parallel with the wires 14 and 2, respectively, the guard rail 20 being parallel with the guard rail 21, and the guard rail 22 being parallel with the guard rail 23 between the bars 16 and 19 and curved outward at 25. The outer end of the guard rails 20 and 23 are slightly curved outwardly, as indicated at 26, to form guides for the current collector 27, shown in dotted lines, Fig. 1, and which is of the form shown in our co-pending application, Serial No. 488,985, filed August 1, 1921.

Connecting the bars 11, 16 and 19 is a bar 28 which braces the same and extends beyond the bar 19 and is connected at its other end to the transverse bar 29. Connected to the bars 16 and 19 by the hangers 30 of the form

shown and heretofore described is a guard rail 31 which extends parallel with the wire 14 and has an outwardly curved end 32.

Connected to or suspended from the bars 5 19 and 29 by hangers 33 is a guard rail 34 which extends parallel with the wire 35 of the branch line. Also suspended from the bars 19 and 29 by brackets 36 is a guard rail 37 which extends parallel with the wire 2 10 of the main line and has its end curved outwardly, as indicated at 38, and upwardly and fastened to a block 39 carried by the wire 2. Connected with the bar 19 is a guard rail 40, which is also supported by the bar 29 said 15 guard rail having its outer end curved outwardly and upwardly at 41 and secured to the block 42 carried by the trolley wire 14. Secured to the bar 29 is a guard rail 43, which has its outer end curved outwardly and 20 upwardly at 44 and secured to the block 45 carried by the branch wire 35. Secured to the bar 29 is a guard rail 46, which has its outer end curved outwardly and upwardly at 47 and secured to the block 48 carried by 25 the wire 1.

From the foregoing description it will be seen that the guard plates are so arranged that a current collector of the character as covered by our pending application as hereinbefore referred to will prevent any liability of a short circuit between the positive and negative wires, and returns the current collector to its proper contact. The negative current is broken at 49 and 50 on the wire 30 1 and at the point 52 on wire 14. We bridge across the insulated area by a wire, as shown at 53, 54 and 55, said wire being supported in any desired manner. The head 27 is provided with the two collecting surfaces 56 35 and 59 separated by the insulating block 58, the collecting surfaces engaging the positive and negative wires, as will be readily understood. The head at the outer end is provided with the retaining plates 57 and 60, which prevent the head from leaving the 40 wires. As a vehicle approaches a switch it naturally turns slightly, causing a pull on the collector head which causes the insulating block 58 to engage the guard rail 4 as 45 the head 27 is guided below the wires. Previous to the block passing off of the guard rail 4 the retaining plate 57 passes between the guard rails 20 and 21, and as the pull of the head is in the direction of the 50 switch the said plate 57 will engage the inner face of the guard rail 20 and travel thereon until the insulated block 58 comes opposite the guard rail 40. The opposite lateral movement of the collector head is 55 prevented by the block 58 engaging the guard rail 31. After the head has traveled along it engages the upwardly curved portion of the rails 41 and 44 and the collector 60 is gradually allowed to raise and pass to the trolley wires, where it again receives the 65

current. If the vehicle is not going to turn, but is going straight ahead, the insulated block 58 will follow the guard rail 5 and the retaining plate 60 of the head will engage the guard rail 23. When the collector 70 reaches the break between the guide rails 5 and 37 it holds the head so that the insulated block will be brought into position against the guard rail 37.

A vehicle entering from the opposite direction on the main line, the insulated block of the trolley head passes between the guard rails 37 and 46. Before the block reaches the end of the guard rail 37 the guard plate 60 passes between the guards 22 and 23 and 75 prevents any material lateral movement of the head. Before the guard plate 60 passes from between the guard rails 22 and 23 the insulated block 58 passes between the guard rails 4 and 5 and is guided by the same so 80 that as the head leaves the same the head is in a position so that the collecting surfaces will engage the wires 1 and 2 and receive the current therefrom. A vehicle entering from the branch line, the insulated block 58 of 85 the head would pass between the guard rails 40 and 43 and be guided thereby. There would be an outward pull on the head to cause the insulated block to ride against the guard rail 40. Before the insulated block 90 passes beyond the end of the guard rail 40 the guide plate 57 of the head would pass between the guard rails 20 and 21, and any material lateral movement of the head is prevented. The insulated block 58 of the 95 head is further guided by the guard plate 31 to cause it to pass between the curved end 13 of the guard rail, whereby it is guided into the space between the guard rails 4 and 5, and in leaving the guard rails 4 and 5 the 100 collecting surfaces are in a position to engage the positive and negative wires 1 and 2.

While I have shown and described this specific arrangement of bars and guide rails, it will be understood that the same could be 105 varied without departing from the scope of our invention, to guide the head as heretofore set forth when passing through a prescribed area, of one polarity at different angles.

When the intersection is at right angles, the guide bars 4 and 5 terminate at the plate 11 and in each case the trolley wheel is free to pass through the said area.

Having thus described our invention, what 110 we claim and desire to secure by Letters Patent is,

1. The combination with a two wire trolley system, of a guard or guide adapted to carry the trolley head of the two wire system down below the trolley wires at crossings, switches or at any desired point.

2. The combination with a two wire trolley system, of a guard supported by the wires, the negative wires insulated there-

- from, and adapted to carry the trolley head, of the two wire system down below the trolley wires, and carry it across switches or crossings out of engagement with the 5 trolley wires.
3. The combination with a two wire trolley system, of a guard supported by the wires and insulated from the negative wire or wires and extending below the wires 10 leaving the free passage for the trolley wheels but adapted to force the trolley head, of the two wire system, down from the wires and carry it across switches, crossings, or a desired area to prevent engagement with the wires or switches or short circuiting the current between the wires.
4. The combination with a two wire trolley system, of a guard supported by the wires and insulated from the negative wire 20 or wires and extending below the wires leaving the free passage for the trolley wheels but adapted to force the trolley head down from the wires and prevent lateral movement of the head, to carry it across switches 25 or crossings,—to prevent short circuiting of the current between the wires and causing the head to resume contact with the double circuit.
5. The combination with a two wire trolley system, of a guard composed of plates having flared ends supported by the wires and insulated from the negative wire or 30 wires and extending below the wires and arranged to force the trolley head below the wires and prevent any material lateral movement thereof.
6. The combination with a two wire trolley system, of insulators inserted in the negative wire or wires, whereby a prescribed area is formed and in which area 40 all wires, switches, crossings are adapted to be of positive polarity.
7. The combination with a two wire trolley system, and within a prescribed area of 45 positive polarity, of guide bars supported by the trolley wires, and adapted to carry the current collector head of the two wire trolley system down below the plane of the trolley wires at switches, crossings, or 50 at any desired point.
8. The combination with a two wire trolley system, of a guard composed of spaced approximately parallel plates, having outwardly flared ends, supported by the wires 55 and insulated from the negative wire or wires and extending below the wires and arranged to allow the free passage of the trolley wheel and force the double contact trolley head below the wires and arranged to 60 prevent any material lateral movement of the head.
9. The combination with a two wire trolley system, of guide bars arranged approximately parallel to the trolley wires, supporting bars connecting said guide bars, and 65
- supported by the trolley wires, the guide bars and support bars adapted to conduct the positive current throughout the prescribed area, means for bridging the negative current over the said area, said 70 guide bars being so arranged to allow the free passage of trolley wheels and force the current collector head of the two wire trolley system down below the plane of the trolley wires, and said guide bars arranged to 75 limit the lateral movement of the head while passing through the prescribed area of positive polarity.
10. The combination with a two wire trolley system, and within a prescribed area of 80 positive polarity, of guide bars charged throughout by the positive wire or wires, and adapted to carry the current collector head of the two wire trolley system down below the plane of the trolley wires at 85 switches, crossings, or any desired point, and resume contact with the double trolley system.
11. The combination with a two wire trolley system, and within a prescribed area of 90 positive polarity, of a guide composed of spaced substantially parallel plates, arranged parallel the wires and having outwardly flared ends, cross bars connecting said plates, means for connecting said plates 95 to the wires below the same to allow the free passage of the trolley wheels and force the double contact trolley head below the wire and said plates arranged to hold the head against any material lateral movement. 100
12. The combination with a two wire trolley system, and within a prescribed area, of positive polarity, of guide bars supported by the trolley wires, and extending down below the plane of the trolley wires, and 105 adapted to force the current collector head of the two wire trolley system down below the plane of the trolley wires, switches, crossings, and carry it under, through and across the trolley wires, switches, crossings, 110 without engagement with said trolley wires, switches, crossings, and cause said head to resume contact with the double trolley system.
13. The combination with a two wire 115 trolley system, and within a prescribed area of positive polarity, of guide bars supported by the trolley wires, said guide bars being so arranged as to allow the free passage of standard trolley wheels in contact with the 120 positive wire or wires, but adapted to force the current collector head of the two wire trolley system down below the plane of the trolley wires, switches, crossings, and carry it under, through and across the trolley 125 wires, switches, crossings, without engagement with said trolley wires, switches, crossings, and cause said head to resume contact with the double trolley system.
14. The combination with a two wire 130

4
trolley system, within a prescribed area of one polarity, of a guide composed of spaced substantially parallel plates arranged substantially parallel the wires and overlapping 5 each other and having outwardly flared ends, means for supporting the plates by the wires below the same to allow the free passage of trolley wheels over the trolley wires, without interrupting the positive current, and 10 said plates arranged to engage the double contact head and force it down below the wires and guide it across the switches or crossings or a desired area and hold it against any material lateral movement and 15 cause the head to again engage the wires.

15. The combination with a two wire trolley system, of a guide composed of spaced parallel plates arranged parallel the wires and having outwardly flared ends, 20 cross bars connecting said plates, the plates and cross bars adapted to conduct the positive current throughout the prescribed area, means for bridging the negative current over said area, means for connecting 25 said plates to the wires below the same to allow the free passage of the trolley wheels and force the double contact trolley head below the wires and said plates arranged to hold the head against any material lateral 30 movement, while passing through the prescribed area of positive polarity and cause the head to resume contact with the negative wire.

16. The combination with a two wire trolley system, and within a prescribed area of positive polarity, of guide bars supported by the trolley wires and extending below the wires, so arranged as to provide a free passage for trolley wheels, but adapted 40 to force the current collector head of the two wire trolley system down below the plane of the trolley wires, to limit the lateral movements of said head, to carry it under, through and across the trolley wires at 45 switches, crossings, and cause it to resume contact with the double trolley system.

17. The combination with a two wire trolley system, and within a prescribed area of positive polarity, of guide bars arranged approximately parallel to the trolley wires, 50 supported by the trolley wires, extending below the plane of the trolley wires, arranged to allow the free passage of trolley wheels, to force the current collector head of the two wire system down below the plane 55 of the trolley wires and to limit the lateral movement of the head.

18. The combination with a two wire trolley system, of guide bars composed of bars arranged approximately parallel to the 60 trolley wires, supporting bars connecting said guide bars, means for connecting said guide bars to the supporting bars, and means for connecting said supporting bars to the trolley wires, to allow the free passage of 65 trolley wheels, and to force the current collector of the two wire trolley system down below the plane of the trolley wires, and said guide bars arranged to limit the lateral movement of said head. 70

19. The combination with a two wire trolley system, of guide bars arranged approximately parallel to the trolley wires and overlapping each other at certain points, causing bearing surfaces for passage of the 75 current collector head, means for supporting said guide bars from the trolley wires to allow the free passage of trolley wheels in contact with the positive wire or wires without interrupting the positive current, said 80 guide bars arranged to engage the current collector head, force it down below the plane of the trolley wires, guide it under, through and across the trolley wires, switches, crossings, or a desired area, limit the lateral 85 movement of the head, and cause the head to again engage the wires.

In testimony whereof we affix our signatures.

CYRUS B. BUCHANAN.
CHARLES C. JOHNSON.
